Patent expires October 30, 1959

4 Claims. (Cl. 20—4)

1

The present invention relates to a building construction comprising a number of individual building sections and to a skeleton keeping said sections together and consisting of a grid of mutually perpendicular joining and coupling bars. Primarily, the invention aims to enable a satisfactory connection between the individual sections by means of the skeleton structure, and particularly has for its object to construct the various parts included in the construction so as to obtain an easily mountable and dismountable structure.

The building sections are rectangular and are adapted to be assembled in edge-to-edge relation by the skeleton to form a wall. As used here and in the appended claims, the term "wall" is intended to include interior and exterior walls, floors, ceilings, and roofs.

The skeleton elements may either consist of bars separated from the building section or consist of parts being at least partly enclosed in the building sections already before assembling the building. The latter arrangement thus produces a beam-like structure which is particularly suited to the use in floor and roof structures. A number of such beam-like structures situated side by side may together form the roof or floor in a building, generally no outer covering on the building section and no particular beams being required since the beam-like building sections act themselves as beams as well as outer covering. In case of roofs the beam-like sections are provided with an outer covering adapted to be applied to the blocks in their manufacture in the factory.

The skeleton elements are substantially of two types, i. e. joining bars and coupling bars. The joining bars are disposed in a groove in an edge of the building section and the coupling bars in a groove in an edge extending transversely thereto or in a channel or bore in the building section extending parallel or approximately parallel with the latter edge. The ends of the coupling bars engage the sides of the joining bar at the point where the joining and coupling bars run together, and said ends are connected by special coupling members at this point.

Some embodiments of the invention will be described hereinafter reference being had to the accompanying drawings wherein:

Fig. 1 is a perspective view of a building according to the invention.

Fig. 1a, an elevation of a section of a wall of the building.

Fig. 1b is an elevation similar to Fig. 1a show-

2

ing building sections held in place by the surrounding and mutually perpendicular joining and coupling bars situated in grooves along the edges of the sections;

Fig. 1c is an enlarged fragmentary perspective of a typical building section showing the joining and coupling bars in place in the grooves;

Fig. 2, a horizontal sectional view of a junction between joining and rail bars in the skeleton on an enlarged scale;

Fig. 3, a transverse sectional view of a coupling bar on the line III—III of Fig. 2;

Fig. 4, a sectional view similar to that illustrated in Fig. 2 but relating to a further embodiment;

Fig. 4a is a transverse section showing the construction of the joining bar and surrounding half-posts, the section being taken at a point axially of the connection point between adjacent coupling bars shown in Fig. 4;

Fig. 5, an end view of a joining bar of the latter embodiment;

Fig. 6, a view similar to Fig. 2 and illustrating a further embodiment of a screw connection in the skeleton;

Fig. 7, a transverse sectional view on the line VII—VII of Fig. 6;

Fig. 8, a view of an assembling tool in a position in the inner of a coupling bar;

Fig. 9, an end view of the tool;

Fig. 10, a horizontal sectional view of the wall illustrated in Fig. 1a and taken at the connection place between two horizontal skeleton elements and a vertical skeleton element, this view illustrating a modified construction for interconnecting the elements;

Fig. 10a, a perspective view of a transverse skeleton element at the connection place;

Fig. 11, a vertical section corresponding to Fig. 10;

Fig. 12, and 12a, perspective views of two different embodiments for the coupling members used in Fig. 10 and 11, on an enlarged scale;

Fig. 13 and 14, a vertical and horizontal section corresponding to Fig. 10 and 11 respectively but relating to a different embodiment of the coupling members;

Fig. 15, an end view of a building section constructed as a beam;

Fig. 16, a perspective view of a similar beam having edge elements;

Fig. 17, a sectional view on the line XVII—XVII of Fig. 15;

Fig. 18, a transverse sectional view of a building section constructed as a box beam,

Fig. 19, a vertical section at the connection place between two wall sections and a floor section constructed as a beam.

Fig. 20, an elevation of a part of a roof.

Fig. 21, a sectional view of a roof covering on an enlarged scale, and

Fig. 22, a vertical section of a roof at the connection place between two roof sections.

It is clear from the perspective view of the assembled building illustrated in Fig. 1 that the building comprises a base *a*, floor sills *b* supported thereby and a skeleton *c* thereon which is enclosed in and connects the building sections *d* forming the walls. The roof *e* consists of sections which are kept together by a skeleton in the same way as the building sections *d* of the walls. A door is designated by *f* and two windows by *g*. Situated at the points of connection between the skeleton elements there are coupling members which are represented by an undulated line *h*. Various possibilities of constructing the connections are illustrated by way of example in the following figures.

Fig. 1a is intended to illustrate the principle of assembling a number of building sections and, for the sake of simplicity represents a wall or part of a wall of the building. The same principle, however, is used in assembling the floor, roof or other building structures. The wall consists of a number of building sections 2, 4, 6, 8 which are kept together by means of the skeleton consisting of joining bars 10, 12 and coupling bars 14, 16.

Two coupling bars are connected with each other by a connection member extending through the joining bar 10 or 12 (Fig. 1a) situated between the ends of the coupling bars. The joining bars 10, 12 are arranged so as to have their joined ends in a non-registering position relatively to the point of connection between the coupling bars, i. e. above or below or laterally of this point.

In the embodiments illustrated in Figs. 2-8 the member connecting the adjoining ends of adjacent coupling bars to maintain the same in an end-to-end relationship comprises a wood screw. Each of the coupling bars consists of two wooden battens or rods 18, 20 (Fig. 3) each having three sides plane and the forth side profiled. This side is formed so as to have a groove 22 in one edge and a tongue at the other edge and a semi-circular channel therebetween. If two such wooden battens are assembled so as to have their profiled sides in engagement with each other and are connected for example by gluing, a coupling bar having a central profiled channel 26 will be obtained. A cylindrical chamber 28 having a diameter equal to or greater than the diameter of the screw head and having a depth equal to the length of the screw is bored in one end of the coupling bar. The wood screw 29 is mounted in this chamber. The chamber is closed by a cylindrical wooden plug 30 introduced from one end of the bar and glued fast in the outer portion of the chamber. The plug is provided with a circular channel 32 the diameter of which is equal to or greater than the diameter of the screw threads.

The ends of the coupling bars may be formed to a tenon or tongue 34 which fits into a groove or cavity 36 disposed in the joining bar.

In assembling two coupling bars 14, 16 and a joining bar 10 (Fig. 2) a screw driver 38 is introduced into one end of the coupling bar. The outer portion of the driver, the blade, has the

transverse section thereof formed to fit into the profiled channel in the bar. As a result the driver cannot be rotated until the blade has been advanced into the chamber 28 which is disposed in the other end of the coupling bar and in which the wood screw 29 is inserted. The driver will be directed exactly towards the screw by the central cylindrical portion of the channel 26 whereby the mounting and dismounting operations are facilitated. By a channel 40 bored in the joining bar 10 (Fig. 2) and having a diameter equal to or greater than the diameter of the screw threads the wood screw is advanced and will engage the other coupling bar 14 in the end of which the cylindrical central portion of the channel 26 has a diameter equal to or greater than the diameter of the screw core. When screw 29 is screwed into the end of coupling bar 14 the two coupling bars as well as the joining bar are secured to each other.

Thus it is characterizing for the coupling bar that it is composed of two complementary profiled interconnected wooden elements having a channel for the introduction of a screw driver and enclosing a rotatable wood screw which is entirely embedded and concealed within the coupling bar. However, it is possible to construct the coupling bar as a single wooden rod, a through channel being bored in the centre thereof for the screws and plugs to be mounted as described.

Alternatively, the coupling bar may be provided with a metallic plug in the form of a screw threaded sleeve or the like in one or both ends instead of a wooden plug. This is illustrated by way of example in Fig. 4. The plug 42 in one end of one coupling bar 16 is provided with a circular channel 44 having the diameter equal to or greater than the diameter of the coupling threads as in the wooden plug 30 described hereinbefore. A similar plug 46 which has inner screw threads is mounted in the opposite end of the other coupling bar 14. These metallic plugs may be cylindrical or conical. The screw consists of a machine screw having a flat head.

The coupling bar may be square or circular in cross section and be surrounded or covered wholly or partly by pressed sheet steel or iron, iron tubes or the like. In Fig. 6 and 7 there is illustrated a bond in which the coupling bars have a circular section and a jacket consisting of a metallic tube 50, and a wooden core 52 with a profiled central channel.

The joining bar forms a tightening and connecting member between building sections which surround the joining bar. Two surfaces of the joining bar are smooth according to Fig. 2 whereas the two other surfaces are provided with the groove 36 in which the tenon or tongue 34 situated at the ends of the coupling bars is inserted. In order to facilitate the introduction of the joining bar into the groove in the building section (for example 4 in Fig. 2) and also the engagement with adjacent building sections (for example 6 in Fig. 2) the joining bar may be made thinner at the edges which are to be disposed inner most in the groove in question than at the central portion as illustrated in Fig. 2.

In one or more points the joining bar is provided with the bored channel 40 through which the screw connecting the ends of the coupling bars is to be introduced. When the screw connects two coupling bars with each other it passes the channel in the joining bar and secures the joining bar in a definite position between the

two coupling bars as a result of tightening the screw:

The joining bar may extend at the entire height (or length) of the building structure or may be divided into shorter lengths as illustrated in Fig. 2, said lengths being constructed in the same manner as the coupling bars so that they may be connected with each other or with a surrounding building section.

The joining bars may have circular section and consist of tubes of iron or other metal (Fig. 6) being constructed in the same manner as the coupling bars.

Plates of wood, artificial mass or the like may be fitted into the skeleton consisting of the joining and coupling bars to form buildings according to the so called plate system.

Post structures can be constructed by this skeleton system by using two so called half-posts 56, 58 (Figs. 4 and 4a) which constitute the sides of two separate building sections and are assembled together with a joining bar 60. The sides of the half-posts facing each other are formed with a groove to receive the joining bar. When the half-posts are put together and enclose the joining bar, the joint therebetween will have no through hole. Also in Fig. 4 the joining bar is presented with a form tapering from the centre towards the edges whereby the joining bar may be easily introduced into the groove of the half-post. The joint is tightened when two half-posts are pressed together by screwing because the maximum thickness of the joining bar will be simultaneously situated exactly in the joint 62 between the two half-posts.

The posts are pressed together by tightening the screws disposed in the coupling bars 14, 16 as hereinbefore described.

At the top and the bottom the half-posts may be confined by or connected with horizontal bars having the same profile as that of the half-post.

Where the joining bar is surrounded by a half-post having tenon holes in which the two ends of the coupling bars are introduced and glued fast or secured in any other way, or the ends of the coupling bars are formed as tenons, no groove is required in the joining bar and no tenon or tongue in the ends of the coupling bars. In such case the half-post is formed so as to prevent any through joint at the point of connection between the coupling bar and the joining bar. According to Figs. 4 and 5 the ends of the coupling bars (Fig. 5) are provided with a cylindrical tenon 64 which engages a corresponding hole in the half-post.

Such elements as are composed of half-posts and in which joining and coupling bars form a skeleton structure as stated above may be used in the production of buildings according to a so called post system. Afterwards panels, plates, artificial mass fillers, and so on may be introduced therewith. In Fig. 4 a panel 66 is shown in connection with the assembled half-posts 56, 58.

Block structures are obtained when the coupling bar is surrounded by a finished building section or plate provided with a groove and produced as one single piece, and when the coupling bars are introduced, glued, or embedded by a moulding process into the building section to the entire length thereof. In such case the groove of the joining bar and the tenon or tongue of the coupling bar end may be dispensed with. Due to the form of the edges of the building element as described no through joint is

obtained at the point of connection between the coupling bar and the joining bar.

Buildings according to the so called block system may be produced by means of such composed building sections of panel, artificial mass, filler and so on which enclose coupling bars forming a skeleton structure together with joining bars as described above.

The screw driver as used when coupling bars and joining bars are connected with each other consists of the driver blade 70, the driver stem 72 and the driver handle 74 (Fig. 8). The driver blade is profiled and formed so as to be easily passed through the profiled channel in the coupling bars 16 and is of such a length that when the screw 29 is advanced into position the driver may be rotated in the inner of the screw chamber 28. The diameter of the stem 72 is such as to allow easy displacement in the channel of the coupling bar the central aperture of which has a diameter equal to the diameter of the screw core. The diameter of the stem is equal to or less than the diameter of the screw core. The stem has such a length that in the screwing operation the handle 74 is situated beyond one end of the coupling bar 16 whereas the driver blade is positioned at the screw at the other end of the coupling bar. The driver handle may be constructed as a separate key having one or more square holes 76 fitting upon the end of the driver stem formed in the corresponding way (Fig. 9).

The order of assembly of the several building sections to form a wall is as follows: With reference to Fig. 1a, the building sections are numbered 2, 4, 6 and 8 and are assembled in that sequence. Starting from the left, the four sections numbered 2, are arranged each above the other with the horizontal coupling bars 16 in place. Joining bars 10 and 12 are then set in place along the right sides of the sections 2 and the two bars 10 and 12 joined in end-to-end relation by tightening screw 400 with a screw driver inserted through the bore in the bar. Next the four building sections 4 with the coupling bars 14 are set in place against the right sides of the sections 2 thus enclosing the joining bars 10, 12. The left end of each of the coupling bars 14 constructed in the manner shown in Figs. 2 or 4 contains a screw, these being numbered 401-406 on the drawing; and are tightened in sequence by pushing the shank of the screw driver 74 through the channel 26 of the bars 14 until the screw is engaged. Joining bars 10, 12 are next fitted in place along the right sides of the building sections 4 and connected by screw 406. The building sections 6 and 8 are then assembled in the same manner as sections 4 and the screws 407-416 are tightened in the order of their numerical sequence. It is to be noted that screws 400, 406 and 412 would of course not be used in cases where the vertical joining bars extend for the entire height of the wall assembly as indicated by joining bar 10 located at the extreme right of the assembly.

Sometimes it is desired to connect two coupling bars and a joining bar situated therebetween in the skeleton system in a manner enabling an elimination of a driver extending through the entire coupling bar from one end thereof to the other. Two different embodiments of connections for this purpose are illustrated in Figs. 10-12 and 13-15 respectively.

According to Figs. 10 and 11 the two building sections 4 and 6 are connected by coupling bars 15, 16 and a joining bar 10 inserted between the

ends thereof in grooves in the facing edges of the building sections 4 and 6 in the manner described hereinbefore. The coupling bars 14 and 16 are connected by a releasable hook bond comprising a hook-like coupling member 80 which is attached to the end surface of the bar 14 by a screw 82, and another hook-like coupling member 84 having a construction similar to that of the first mentioned member and engaged therewith. The member 84 is secured to the bar 16 by a screw 86. The hook-like members are situated, in their mounted position, within an aperture 88 which is provided in the joining bar 10 (Fig. 10a).

The hook member as illustrated in Fig. 12, consists of a plate 90 having a hole for mounting the screw 82 and a flange 92 projecting from one edge, a gripping portion 94 extending in spaced relation to the plate 90 parallel therewith. The gripping portion has an oblique side 96 facing the plate so that the gripping portion tapers towards its outer edge. A wedge-shaped space 97 is present between the gripping portion 94 and the plate 90. Opposite to the screw hole in the plate 90 the gripping portion is provided with an aperture 98 through which the screw is available.

As illustrated in Fig. 12a the front edge of the flange 92 is provided with a slot 99 extending below the aperture 98. Formed on the plate there is also a projection 100 which suitably tapers from its base and outwardly. This projection is adapted to engage the slot 99 in the other hook-shaped coupling member when two such members are brought to engage each other in a connecting relation. The projection 100 serves as a guide preventing lateral displacements between the coupling members.

When a coupling member of the construction illustrated in Fig. 12 is to be connected with another similar coupling member, this is effected by bringing the latter member in a turned-down position, i. e. with the thin outer edge of the gripping portion 94 turned downwards to engage the former member from above so that the gripping portion 94 of one member 80 enters the wedge-shaped space 97 between the gripping portion 94 and the plate 90 of the other member 80a (Fig. 11), the oblique surfaces 96 of the two members engaging each other. A good wedge-like engagement is thus obtained, and the coupling members have a tendency of moving the ends of the coupling bars to which they are secured towards each other as the gripping portions 94 are being brought further into the wedge-like spaces (Fig. 11). The aperture 88 of the joining bar continues upward with a cavity 89 which enables introduction of the coupling member 80a above the coupling member 80 so that it may be deposited to engage the latter.

Where the coupling members are provided with guiding projections 100 as illustrated in Fig. 12a care should be taken during the coupling operation that the projection of one member engages the slot 99 of the other member thus effecting also a lateral locking relation.

In the embodiment illustrated in Figs. 13-14 the coupling between the coupling bars 14, 16 comprises partly a rotatable locking hook 102 having a shaft 104 journaled in a bracket 106 on one coupling bar and partly a stationary locking member secured to the other coupling bar and being formed so as to enable the rotatable locking hook to engage it and effect a locking relation. The locking hook consists of a plate attached to the shaft 104 and having its periphery

shaped spirally and provided with a corresponding flange 110. This flange or rim begins at an edge 112 of the plate and from this edge runs spirally at a radial distance from the shaft 104 which decreases successively. The locking portion 108 is provided with a fork-shaped head the shanks 112 of which are provided with inwardly directed projections 114 the opposite faces of which are disposed in such a distance from each other that the plate-shaped portion of the locking hook is free to be introduced therebetween simultaneously as the peripheral flange 110 can be advanced between the fork shanks at the inner side of the projections. The locking portion 108 is further provided with a screw-threaded stem 116, by means of which it is screwed and fixed into the coupling bar 14. The bracket 106 is formed as a clamp for the locking hook 102 and is secured to the bar 16 by a screw 118. The shaft 104 of the locking hook is carried in upwardly open slots 120 in the shanks of the bracket. In one end of the bar 16 there is a cavity 122 in which the bracket 106 is fitted, and corresponding cavities 124 may be present in the building section 6 if needed to get sufficient place for the locking hook.

Figs. 15-18 illustrate building sections constructed as beams or girders and contemplated to be included in a building structure according to the invention. Such a beam or girder may form an intermediate floor or ceiling in a building but may also be used as a wall section.

The girder shown in Fig. 15 has its web constructed as a number of wooden bars 202 in spaced relation to one another, the flanges consisting of battens 204 which are suitably notched and are mounted in such position on the bars as to have their direction of fibre extending transversely to the wooden bars. The wooden bars are fixed to the battens, for example as shown, by means of a dove-tail bond 206, and thus the entire element has substantially the qualities comparable with those of an I-girder.

To enable connection of two girder type building sections of this type positioned in lateral engagement with each other and with the ends of the bars 202 of the various sections opposite to each other, the bars are provided with longitudinal channels 208 which suitably extend wholly through the bars and contain suitable connection means such as a screw or hook in one end of the bar and a corresponding screw threaded sleeve or bore, hook or loop in the other end. The channel may be formed with such a section that a suitable tool such as a screw-driver can be inserted and guided therein when the connection is to be established. The detailed construction of the connection means may be as illustrated in Figs. 2, 4, 6 or 10, 11 or 13, 14.

As an alternative or supplement of these connection means, reinforcing irons adapted to strengthen the girder may be inserted in all or some of the channels in the bars.

To enable suitable connection of the girder or beam with similar or different building sections positioned in planes which form an angle with the plane of the girder, the girder may be provided with edge pieces or projections 210 at the flange edges parallel with the wooden bars as shown in Fig. 16. The flange edges are countersunk and secured in grooves in the edge piece.

The ends of the webs 202 may be arranged with edge pieces 212 according to Fig. 18 so that the entire girder or beam forms a closed box. The outer side of the edge piece 212 may have longi-

tudinal grooves 214 to receive an edge bar 216 which also is to fit into a similar groove in a similar box shaped girder or beam placed adjacent to that illustrated.

Fig. 19 illustrates a connection between a girder or beam having a web 202, flanges 204 and an edge piece or projection 210 according to the invention on one hand and a pair of other building sections 218, 220 extending in a plane at right angles to that of the girder or beam on the other hand. The girder or beam may form part of a flooring in a building in which the section 218 forms part of a wall in an upper floor and the section 220 forms part of a wall in a lower floor. The building sections 218 and 220 may be substantially constructed as is the girder or beam. Numeral 222 designates joining bars between the edge element 210 and the coupling bars in the wall sections 218, 220.

Where the girder or beam is included as a part of for example a flooring or wall of a building it may be provided with a covering of any suitable kind produced for example by painting, papering and so on.

Figs. 20-22 illustrate details of a roof which may be included in a building construction according to the invention. The roof comprises a number of sections 302 which suitably extend from the roof-tree to the lower edge of the roof and are separated by joints 304 which are formed between the edges of the sections positioned side by side. The sections are suitable to manufacturing in a factory. For example they may consist of tongue and groove connected battens 306 and are each provided with a protecting covering 308 on the top and are produced with this covering in their finished state in the factory. The battens 306 are kept together by transverse bars 307 having connection means inserted therein to enable connection of the section with other sections included in a roof. The bars and the connection means are included in the finished section as produced in the factory. Generally the bars are shorter than the breadth of the roof section so that between each pair of adjacent sections there is a space between the bar ends to receive a roof truss element 309 or the like supporting the section. A coupling member 311 extends through the roof truss element between the bar ends. This coupling member while shown as a wood screw may also be of any of the other types described in connection with Figs. 4, 6, or 10, 11, or 13, 14.

The covering consists of a layer 310 of asphalt or the like (Fig. 21) and a foil 312 of metal, cellophane or the like embedded therein. At the top there is a thin layer 314 of crushed mineral raw substance of any suitable colour for example crushed gravel, potstone chips, or the like. The asphalt to be employed should suitably have a low point of plasticity so that it may be deformed to a certain extent without the generation of cracks. According to certain tests the asphalt generally is porous to a certain extent and as a consequence is not entirely sealing. The necessary sealing condition is thus obtained by the foil which may advantageously consist of a aluminium foil. To prevent breaking thereof in case of stresses generated due to displacement of the support at changes of temperature and moisture the foil is folded or undulated.

In addition to the foil the covering may contain or have a support consisting of a layer of jute-cloth, wire net or the like.

To prevent water from penetrating into the joints between the roof panel sections the marginal portions thereof which after mounting the

section extends from the roof tree and downwards along the roof, i. e. the marginal portion close by the joints 304 may be projecting upwards and be formed to support a sealing strip 316 of for example sheet metal as illustrated in Fig. 22. Said sealing strip may be substantially T-shaped in cross section having the portion corresponding to the vertical part of the T introduced into the space between the panel sections, where's the remainder thereof extends as a roof above the joint and the adjacent marginal portion of the panel sections. The sealing strip may be made from a single strip of sheet metal which has been double-folded along a longitudinal line whereupon one of the folded shanks has been bent to stand at right angles to the other.

What I claim is:

1. A wall comprising a plurality of abutting rectangular wooden panels having grooves in the longitudinal and transverse edges thereof, and a wooden skeleton connecting said panels together in edge-to-edge relation to form an unbroken surface, said skeleton comprising wooden joining bars disposed in the grooves along one pair of opposite edges of said panels, wooden coupling bars disposed in the grooves along the other pair of opposite edges of said panels, said coupling bars being sectionalized to provide a joint therebetween at each joining bar and with the adjoining ends of adjacent coupling bars abutting opposite sides of the joining bar, each said coupling bar including an axial channel extending longitudinally therethrough, the configuration of said channel in a plane normal to the longitudinal axis thereof including a circular central portion and diametrically opposite slots extending therefrom to permit guided insertion of the shank and blade of a screw driver, a headed screw concealed from view, and means retaining the screw head in said channel at one end of said coupling bar, the shank of said screw extending outwardly of the bar end through an aligned transverse aperture in said joining bar and threadedly engaged with the adjoining end of the adjacent coupling bar.
2. A wall as defined in claim 1 wherein each said coupling bar is comprised of two wooden strips joined longitudinally in face-to-face relation, said strips each being provided with co-registering longitudinal grooves establishing the said channel in the bar.
3. A wall as defined in claim 1 wherein one end of the channel in each said coupling bar terminates in a screw chamber, and said screw head retaining means is comprised of a bored plug secured within said chamber, the shank of said screw extending outwardly through the bore in said plug and the screw head being retained against longitudinal displacement by said plug.
4. A wall comprising a pair of grooved panels arranged in edge-to-edge relation to form an unbroken surface and means securing said panels together in edge-to-edge relation, said securing means comprising a pair of bars arranged in end-to-end relation in the grooves of said panels, each said bar including an axial channel extending longitudinally therethrough, the configuration of said channel in a plane normal to the longitudinal axis thereof including a circular central portion and diametrically opposite slots extending therefrom to permit guided insertion of the shank and blade of a screw driver, a headed screw concealed from view within said bars joining adjacent ends of said bars in end-to-end

relation, and means retaining the screw head in the channel of one of said bars at one end thereof for engagement with a screw driver when inserted through the channel from the other end of the bar, the shank end of said screw projecting outwardly from the bar end and threaded into the adjacent end of the other of said bars.

CARL AUGUST AJNE.
